UNITED STATES PATENT OFFICE.

JOHN H. JOHNSON, OF CHARLESTON, SOUTH CAROLINA, ASSIGNOR OF ONE-FOURTH
TO THOMAS MARKS, OF CHARLESTON, SOUTH CAROLINA.

RAILWAY-CAR LOADER.

Application filed June 14, 1922. Serial No. 568,101.

To all whom it may concern:

Be it known that I, JOHN H. JOHNSON, a citizen of the United States of America, residing at Charleston, in the county of 5 Charleston and State of South Carolina, have invented certain new and useful Improvements in Railway-Car Loaders, of which the following is a specification.

My present invention relates to improvements in railway car loaders adapted especially for use with ditching machines, for scooping up or receiving the plowed material and loading said material upon a dirt car from whence it is later dumped or otherwise emptied. The invention contemplates an equipment to be carried by any well known type of standard railroad dump car, and to follow a ditching machine carried by a preceding railway car which is adapted to 10 plow the dirt at the side of the railway road bed in the formation of the standard ditches. Two or more of the dirt cars are utilized to follow the ditching car and the work train is pushed or pulled by a locomotive whereby 15 the ditch is plowed, the material is gathered by the succeeding car loader, conveyed alongside the car and dumped or deposited in the interior of the car from the conveyer or conveyers carried by said car. 20 The equipment as utilized on the railway dump car is adapted to conform to the requirements as to dimensions of standard railroads; may be folded or stored within the required limits on the railway car for transportation, or to permit passage of the regular railway traffic, and is operated by the moving car which thus becomes self-loading, and from which the material may be dumped or otherwise disposed of in suitable manner. 25 As embodied in my invention the construction and operation of the equipment is greatly simplified over devices heretofore used for similar purposes, the cost of construction, operation and maintenance are materially reduced, and both time and labor are saved in the formation of ditches alongside the tracks and in the disposal of the plowed material. 30

The loading equipment may be used at 35 either one or both sides of a railway car, and while I have illustrated and described the equipment in detail at only one side of the car, it will be understood that the use of the loader is contemplated at both sides. Some 40 details of construction and minor acces-

sories have been omitted in the interest of convenience of illustration, but it will be understood that the invention embodies all the features necessary for the practical application of the principles of my invention. 60

In the drawings:

Figure 1 is a view in side elevation showing the general assembly of parts involving a ditching car and a rear loading car for plowing and gathering the plowed material 65 at the right side of the railway track.

Figure 2 is a detail sectional view, transversely of a railway car, showing the conveyer carried at one side thereof, and in inoperative position, as for transportation. 70

Figure 3 is a detail, top plan view partly in section of one of the U-shaped stirrups and its hinge for supporting the conveyer at the side of a car. 75

Figure 4 is an enlarged, detail view in side elevation, showing the front end of the conveyer, the elevator, the front scoop and supporting means therefor carried by the ditching car in front of the loading car. 80

Figure 5 is a top plan view of the parts of Fig. 4, some parts being omitted for convenience of illustration. 85

Figure 6 is an elevation at the rear end of the loading car, showing the operating means for the conveyer. 90

Figure 7 is a detail view at the front of the scoop, showing the supporting frame in section carried by the plow or ditching car in front of the loading car.

Figure 8 is a view in side elevation at the rear end of the loading car, showing the truck and wheels in dotted lines. 95

Figure 9 is an enlarged, transverse sectional view at line 9—9 of Figure 8. 100

Figure 10 is an enlarged, sectional view of one of the conveyer-supporting brackets at line 10—10 of Figure 8. 105

Figure 11 is a detail view partly in section showing the manner of mounting the driving shafts for the conveyer. 110

Figure 12 is a transverse sectional view at line 12—12 of Figure 11.

In the assembly view of Figure 1 the relation of parts may be understood and their functions ascertained by reference to the several parts as a whole which comprise the equipment. The dirt loading car 1 is of standard form for a railway dump car, and of course has the usual trucks and wheels, as 2, one of the wheels, or rather its axle 115

being utilized for operating the loading machine as will be described. The forward car designated as 3 is a standard flat car with wheels 4 and the cars 1 and 3 are coupled together to be pushed or pulled by a locomotive for the ditching and loading operations. A plow is indicated at 5 and carried by the car 3, and this plow and connections form the subject matter of a pending application for patent Ser. No. 568,102, filed Jan. 14, 1922, wherein the details of construction are more elaborately illustrated.

The loading equipment comprises a front scoop 6 and hopper 7, supported from the ditching car as will be explained; an elevator designated as a whole by the numeral 8 and a conveyer carried by the loading car and designated 9. The scoop follows the plow 5 and gathers the plowed material, passing it to the hopper 7, where the material is caught by an endless conveyer and elevated to the conveyer 9 and as the material passes longitudinally of the car it is dumped or guided to fall into the interior of the dump car 1. The conveyer and elevator are operated from the driving mechanism designated as a whole by the numeral 10, at the rear end of the loading car.

One or two of the conveyers may be utilized as desired, one located at each side of the loading car, and these conveyers, which, when in working position are supported and suspended along the top of the car at its sides, may be folded bodily, or lifted over into the car by means of derricks or cranks 11, 11, near the ends of the car. The ditching car also carries derricks or cranes 12, 12, for manipulating the ditching plow and its supporting frame and the scoop and elevator. The hoisting mechanism of the derricks or cranes may be manually operated, or may be power operated, as by air engines.

Inasmuch as the description of one loading equipment is the same as the other, reference will be made to the equipment illustrated as working at the right hand side of the car, it being understood that this description is applicable to the other loading and conveying mechanism.

The endless conveyer which extends from the rear end of the loading car to the scoop 6 includes an endless sprocket chain 13 of usual type, which is supported at the operating end on the driven sprocket wheel or drum 14, and its front end on the guide wheel 15 (Fig. 7) within the hopper 7. The lower flight of the endless conveyer is the working flight and conveys the material to the rear or toward the rear of the loading car, from the elevator and hopper. A suitable number of upright scraper blades 16 are carried by the chain 13 to perform the function of buckets, and it will be apparent that these blades are disposed at an angle

to the path of travel of the blades, in order that the material conveyed may be shifted toward and into the interior of the car 1. At the front of each scraper blade is attached by rivets a plate 17 and this attaching plate is fashioned with an upright rib 18 extending the full height of the scraper blade and coupled to the endless chain 13. At its outer end, or the end remote from the chain 13, said rib has an extension or projection 19, beyond the edge of the scraper blade. The endless conveyer passes through a longitudinally extending trough or housing 20 somewhat U-shape in cross section and provided with a bottom 21 through which a central groove 22 extends as a path and guideway for the projections or guide lugs 19 of the scraper blades in their working passage.

The trough is also provided with a continuous, centrally slotted sheet metal guide plate 23, near the top for the upper flight of the conveyer, and intermediate diagonal, vertical and horizontal brace straps of metal form a lattice work as 24 for reinforcing the trough and maintaining it in working position. The conveyer trough is thus fashioned as a strong, durable, and comparatively light, metallic structure that may with facility be moved from position of Figure 2 to the working position of Figure 9, by utilization of the derricks 11 and their hoisting tackle.

When in working position of Figures 8 and 9, the conveyer is suspended and supported at the side of the car, designated as a whole by the numeral 25. A series of U-shape stirrups 26 are utilized to suspend the conveyer, and these stirrups are distributed or spaced at regular intervals, say 3 feet, along the side of the car as holders for the trough. The stirrups are all hinged to the car, and each is fashioned with a forked or bifurcated head 27 that is perforated, and adapted to straddle a guide beam 28. Each stirrup has a complementary guide beam, extending transversely of the car and affixed thereto in suitable manner, and the guide beam is fashioned with a longitudinally extending slot, which is disposed transversely of the car, and designated 29. Hinge pins 30 are passed through the bifurcated and perforated heads 27 and the slotted beams and cotter pins or retaining pins 31 are used for holding the pins in place. One or more of the stirrups may be supplied with eye bolts 32 to which hooks of the hoisting tackle may be applied, and the cranes or derricks 11, 11, may be used for manipulating the conveyer. By use of the crane the stirrups with their pins in the slots 29 may be slid horizontally and transversely of the car in position of Figure 2, and when the pins reach the ends of the slotted beams 28, the stirrups which now

suspend the conveyer, swing over and downwardly into position of Figures 8 and 9, and the conveyer is thus suspended in working position.

5 The conveyer is also supported in working position by a series of spaced, independent brackets, located below the conveyer, and indicated by the numeral 33. These brackets are foldable, and when not in use may be 10 turned around parallel with the side of the car for transportation purposes and to remove any obstructions from the side of the car. Each bracket 33 is provided with a hinge sleeve 34 for the hinge bolt or pin 35 15 which is supported on and in the spaced eye members 36 affixed to the car side. A suitable number of the foldable brackets are provided beneath the conveyer, which receive the weight of the conveyer when lowered to working position, and relieve the 20 stirrups of the strain of the entire load, thus distributing the weight between the suspending stirrups and the supporting brackets. When not in use the brackets are folded or turned around on their hinge pins 25 parallel with the car side, and if necessary devices may be utilized for holding the brackets close to the car wall.

Each of the endless conveyers is actuated 30 by movement of the loading car, and they may be operated either singly or in pair from a driving sprocket wheel 37 on one of the car axles as 38. A clutch device 39 is provided on the axle by means of which the 35 driving mechanism may be connected and disconnected, and suitable operating means for the clutch will of course be provided. A driving sprocket chain 40 passes around the driving sprocket 37 and over a driven 40 sprocket wheel 41 on the power shaft 42. The power shaft extends transversely of the car and is elevated above its deck with its journals in bearings 43 in a frame 44. Above the power shaft are two counter- 45 shafts 45 and 46 for driving the right hand and left hand conveyers respectively, and these shafts are journaled in removable or universal bearings 47 in the frame 44. As the main sprocket wheels and their shafts 50 45, 46, are foldable with the conveyer mechanism. The inner bearings 47 for the shafts 45 have removable caps 47^a and are provided with bushings 47^b having trunnions 47^c in the bearing. The outer bearing caps 47^a are 55 hinged, in order that, after these caps are swung upwardly from the shafts and the caps 47^a removed, the shafts 45 and their respective sprocket wheels may be swung upwardly on the trunnions 47^c as centers to 60 bring the sprocket wheels to inoperative position within the sides of the car. The conveyer may be disconnected from the sprocket wheels if necessary in such manner as is required to permit the swinging movement 65 of the shafts.

The power shaft 42 has a pair of spaced, main gears 48 revoluble therewith, and these gears engage pinions 49 forming members of clutch devices 50, 50 on the respective shafts 45, 46. The clutch mechanisms 70 50 are provided with usual operating levers to throw them into and out of engagement in order that the short shafts may be revolved from the power shaft, and thus, in addition to the main clutch 39 on the axle 75 38, either of these two clutches 50 may be utilized, or both may be used to render the conveyers operative.

The conveyer extends alongside the car in an elevated position, and the elevator 8 declines from the forward end, where it is jointed to the conveyer by hinge joints 51 and 52, which may readily be connected or disconnected for assembling the parts or for dismantling the equipment. And the elevator 8 through which the endless conveyer passes is made flexible by the use of metal straps 53 with loose pivot joints 54 in order that it may be adapted with facility and maintained in proper working position for guiding the endless conveyer. These metal suspension straps connect the upper portion of the elevator with the lower trough portion 55 to form a stable support for the traveling 90 mechanism of the conveyer. 95

At the lower or front end of the declining elevator 8 a shaft 56 is transversely disposed and journaled therein for the guide sprocket wheel 15 of the chain 13, and near the ends of this shaft guide wheels 57 may be used to guide the blades of the conveyer as they pass around the shaft and scrape up the material from the bottom of the hopper 7.

The material of course is gathered at the front open end of the scoop, and at its rear end the scoop has a pair of side wings 58, vertically disposed, to close the lateral opening and make connection between the rear end of the scoop and its hopper, thus preventing loss of material. A hinge joint 59 is provided in the bottom of the scoop at its rear end between the scoop and the connection 58 to the hopper, in order that the working or forward end of the scoop may be elevated or lowered with relation to the ground surface for gathering the material. 105 110 115

The scoop is of a U-shape with an inclined bottom and is suspended from a set of suspending rods 60 located preferably at its four corners, and at their lower ends these rods are pivoted at 61 to the lower portion of the scoop. The suspending rods are vertically disposed and supported in brackets 62 through which the upper threaded ends of these rods pass, and the threaded ends of the rods are equipped with hand wheels 63 by means of which the respective suspending rods may be raised or lowered. Thus by manipulating the hand wheels the elevator, 120 hopper, and scoop may be adjusted, and the 125 130

scoop also may be adjusted on its hinge joint. The brackets 62 are bolted or otherwise attached to a plow frame 64 that is located at the side of the ditching car and 5 carries the plow 5. This frame is hinged to the ditching car and after the loading mechanism has been detached therefrom, the frame may be turned up over the side of the flat car 3.

10 At 66 in Figure 4 a perforated lug is shown on the hopper 7 to which the hoisting tackle of one of the cranes 12 may be connected for raising or lowering the loading mechanism, and this tackle remains in place 15 to support the elevator and scoop while the equipment is working.

The material is carried to the rear by the angularly disposed scraper blades passing through the conveyer trough, and the action 20 of the blades results in scraping or shoving the material through an opening in the side of the car, where it is deposited in the bottom of the dirt car. This car may have the usual inclined bottom sections, and dump 25 the material through open doorways at the sides of the car, or any other suitable type of dirt car may be utilized.

One or more of the dirt cars may be used to convey the material, and in such case the 30 conveyers are connected between the cars to form a continuous conveyer from end to end of the train. As many cars may be loaded as the engine can pull, the last car, as the car designated 1, being equipped with the 35 driving mechanism for the conveyer, while the first car of the train is provided with the scoop and elevator portion of the conveyer. While the plowing device which precedes the loading conveyer is shown herein 40 as the subject matter of a co-pending application for Patent Ser. No. 568,102, filed June 14, 1922, it will be understood that any suitable type of plowing or ditching machine may be used ahead of the loading 45 cars, and in this manner the ditch may be formed, the plowed material gathered, and loaded on the dirt train with practically one operation as the locomotive pulls the train ahead.

50 After the ditching and loading operations have been completed, the bearings for the shafts 45 and 46 may be released, the scoop and elevator disconnected from the conveyer after removal of bolts 51 and 52, and disconnection of the required links in the upper and lower flights of the chain conveyer and stowed away on the ditching car 3 by means of derrick 12, and then the conveyer at the 55 side of the car is swung on its hinge joints at 27, to horizontal position, and slid in-board to clear the side of the car as in Figure 2.

The cranes or davits 11 are of course removable and may be dismantled and stowed away when not in use, to keep the height of

the dirt car within the required dimensions for railway traffic.

Having thus fully described my invention, what I claim as new and desire to secure by Letters Patent is:

1. The combination in a railway car loading equipment with a hinged, foldable trough and endless conveyer, of a detachable elevator at the front end of said trough, and an adjustable scoop at the front end of 75 said elevator.

2. The combination in a railway car loading equipment with a longitudinally extending, hinged conveyer trough and an endless conveyer therein, driving mechanism carried by the car and actuated from an axle thereof, an elevator at the front end of the conveyer trough, and a scoop at the front of the elevator.

3. The combination in a railway ditching and loading equipment with a ditching car and a loading car, of a hinged conveyer trough on the loading car and an endless conveyer therein, operating means for the conveyer; a detachable elevator at the front of the conveyer trough and forming part of the endless conveyer, a scoop connected with the elevator, and means on the ditching car for supporting said scoop.

4. In a railway ditching train the combination with a ditching car and a loading car, of a hinged conveyer trough carried by the loading car, a detachable elevator connected at the forward end of the trough between the two cars, an endless conveyer in said trough and elevator and driving mechanism for said endless conveyer actuated by movement of the loading car, a hinged scoop at the forward end of the elevator, and adjustable means on said ditching car for supporting said scoop.

5. The combination in a railway loading car with a side conveyer trough and conveyer mechanism therein, of spaced suspending stirrups each having a hinged and sliding connection with the car, means for disconnecting the conveyer mechanism, and means for swinging the stirrups and trough upwardly and over the car to inoperative position.

6. The combination in a railway loading car with a side conveyer trough, of spaced U-shaped suspending stirrups each having a hinged and sliding connection with the car, and means for swinging said stirrups and trough upward and over the car to inoperative position.

7. The combination in a railway loading car having slotted, transversely disposed guide plates, of a side conveyer trough, U-shaped suspending stirrups for said trough having hinged sliding connection with said guide plates, and means for swinging said stirrups and trough upward and over the car to inoperative position.

8. The combination in a railway loading car having transversely disposed, slotted guide plates, of a side conveyer trough, foldable brackets attached to the car beneath the trough, suspending stirrups for said trough, hinged-sliding connections between said stirrups and guide plates, and means for swinging said stirrups and trough upward and over the car to inoperative 10 position.

9. The combination with a railway load-

ing car, of a hinged and foldable conveyer trough at the side of the car, an endless conveyer in said trough including angularly disposed scraper blades for passing material 15 into the car, and means on said blades co-acting with the trough for guiding said endless conveyer.

In testimony whereof I have affixed my signature.

JOHN H. JOHNSON.
